UNITED STATES PATENT OFFICE.

PHILIP T. DODGE, OF WASHINGTON, DISTRICT OF COLUMBIA, ASSIGNOR TO MERGEN-THALER LINOTYPE COMPANY, A CORPORATION OF NEW YORK.

KEYBOARD MECHANISM FOR LINE-CASTING AND KINDRED MACHINES.

1,120,458.

Specification of Letters Patent.

Patented Dec. 8, 1914.

Application filed September 28, 1910. Serial No. 584,243.

To all whom it may concern:

Be it known that I, PHILIP T. DODGE, of Washington, in the District of Columbia, have invented a new and useful Improvement in Keyboard Mechanism for Line-Casting and Kindred Machines, of which the following is a specification.

My invention has reference to mechanism of a general character represented in Letters Patent of the United States to Philip Tell Dodge No. 530931 dated 18th December, 1894.

The mechanism of this class of escapement device for releasing the type matrices from their magazines is actuated by power driven devices controlled by finger keys. In practice it sometimes happens that the movement of the escapement mechanism is resisted by the presence of the matrix in an improper position or by other causes and in such event it is necessary that provision should be made for relieving the parts of the strain to which they would otherwise be subjected by the driving mechanism.

My invention has reference to improved means for relieving the parts from strain and to this end consists in a yoke or lever for actuating the reeds provided with a spring of such strength that while it would operate the reed and escapement under ordinary conditions it will yield in the event of the escapement meeting with undue resistance.

With the exception of the parts herein-after described and specifically claimed the mechanism may be in all respects of the ordinary or any suitable construction.

Referring to the drawings, Figure 1 is a vertical section of an escapement mechanism and the parts for actuating the same through the lower end of the magazine. Figs. 2, 3, 4 and 5 are views showing alternative or equivalent forms on which a spring may be applied.

Referring to Fig. 1 *a* represents an inclined channeled magazine adapted to carry the matrices *b*. *c* represents one of the series of escapement levers mounted on a central pivot and provided at opposite ends with two upwardly extending pawls which are alternately projected into and withdrawn from the magazine by the vibration of the lever. *d* is a spring acting on the

rear end of the escapement lever and holding the forward pawl in an elevated and operative position as shown in the drawing. *e* is a vertical reed mounted in guides *f* and *g* and positioned to act beneath and lift the rear end of the escapement lever to effect the release of the matrix. *h* is a horizontal yoke or lever mounted at one end on a horizontal pivot *i* and arranged at the opposite end beneath the reed *e* for the purpose of lifting the same. The cam yoke *h* contains a cam *j* mounted on a horizontal pivot in the yoke. *k* is a horizontal constantly driven roll extending across the entire width of the keyboard serving to operate the entire series of cams and yokes, of which there is one for each channel in the magazine. *l* is an angular dog mounted on a horizontal pivot in position to engage beneath the yoke *h* in order to sustain the latter at such height as to prevent contact between the cam *j* and the roll *k*. *m* is a vertical slide connected at one end with the dog *l* and arranged to be lifted at the lower end by the finger key lever *n* which is pivoted midway of its length. *o* is a stationary pin or stop arranged to engage the cam *j* when the latter is in its elevated position in order to prevent its heavier side from falling prematurely into engagement with the roll *k*.

So far as described the parts are of ordinary construction. When the key lever *n* is actuated the bar *m* disengages the dog *l* from the yoke *h* which descends by gravity, permitting the cam *j* to engage with the underlying roll *k* and disengage from the stop pin *o*. As soon as this occurs the friction between the roll *k* and the cam *j* causes the latter to turn upon its axis and owing to the eccentricity of the cam, which is supported for the time being on the surface of the roll *k* it acts in turn to lift the yoke *h* to and above its original position, causing it in turn to lift the reed *e* and actuate the escapement. The finger key being released the dog *l* assumes its original position and arrests the yoke when the latter falls to the original level.

In the mechanism heretofore constructed it has been customary for the yoke *h* to act directly against the lower end of the reed *e*. Carrying my invention into effect I introduce between the lower end of the reed *e*

and the yoke a spring of any suitable form attached to or carried by the yoke, so that in the event of the escapement lever and reed offering an excessive resistance to the rise of the yoke the spring may yield and permit the yoke to rise without undue strain upon the parts.

In Figs. 1 and 2 P represents this spring in the form of a flat leaf seated on top of the yoke and secured thereto by rivets *p* passing through ears bent down from the sides of the spring at its rear or near end. The outer end of the spring stands above and out of contact with the yoke and it is of strength sufficient to overcome the resistance of the escapement spring *d* and cause the proper operation of the escapement under normal conditions.

In Fig. 3 P represents the spring of U form made of sheet steel or equivalent metal, the lower end being riveted to the under side of the yoke; it is extended forward and upward and returned over the top of the yoke and positioned to receive the lower end of the reed *e*.

In Fig. 4 the spring *P²* is of spiral form and is seated on the upper side of the yoke around the stem or spindle formed on the lower end of the reed *e* and extended down through a hole in the yoke.

In Fig. 5 the spring of spiral form is seated in a vertical hole in the yoke beneath the lower end of the reed *e* which is extended downward into the hole.

It will be noted that in each instance the yoke carries or supports the spring, which in turn actuates the reed. The construction is simple and inexpensive. It prevents the possibility of the breakage of the escapement or of the injury to matrices thereby. The application of the spring to the yoke is advantageous in that it makes the parts to be readily assembled, readily inspected, and also in that it permits each yoke to be individually and quickly removed in the event of the spring needing adjustment or replacement.

Having thus described my invention, I

claim and desire to secure by Letters Patent:

1. In a keyboard mechanism of the class described, the combination of an actuating reed, a movable horizontally-disposed cam yoke for operating the reed and arranged in immediate proximity thereto, said yoke being pivotally mounted at one end, and a spring interposed between the other end of the yoke and the reed and through which the operating movement of the yoke is transmitted to the reed.

2. The combination of a linotype escapement, a keyboard cam for actuating it, and a cam yoke embodying a bearing member co-operative with the cam and a resilient member straddling the cam, one end of said resilient member being rigidly attached to said bearing member and the other end being yieldable and co-operative with the escapement-actuating means.

3. In a keyboard mechanism of the class described, the combination of an actuating reed, a movable, horizontally-disposed cam yoke for operating the reed, said yoke being pivotally mounted at one end, and a spring interposed between the other end of the yoke and the reed and carried by the yoke, and through which the operating movement of the yoke is transmitted to the reed.

4. In a keyboard mechanism of the class described, the combination of an actuating reed, a movable, horizontally-disposed cam yoke for operating the reed, said yoke being pivotally mounted at one end, and a yielding element arranged in engagement with the other end of the yoke and the lower end of the reed and through which the operating movement of the yoke is transmitted to the reed.

In testimony whereof I hereunto set my hand this 21st day of September, 1910, in the presence of two attesting witnesses:

PHILIP T. DODGE.
